US00D897048S

(12) **United States Design Patent** (10) **Patent No.:** **US D897,048 S**
(45) **Date of Patent:** **** Sep. 22, 2020**

(54) **PET CAGE**

(71) Applicant: **Iris Ohyama Inc.**, Sendai-shi, Miyagi (JP)

(72) Inventor: **Soma Okayama**, Kakuda (JP)

(73) Assignee: **IRIS OHYAMA INC.**, Sendai-shi (JP)

(**) Term: **15 Years**

(21) Appl. No.: **29/686,916**

(22) Filed: **Apr. 9, 2019**

(30) **Foreign Application Priority Data**

Oct. 15, 2018 (JP) 2018-022595
